US00D880501S

(12) **United States Design Patent** (10) **Patent No.:** **US D880,501 S**
Shadforth et al. (45) **Date of Patent:** **** Apr. 7, 2020**

(54) **DISPLAY SCREEN WITH GRAPHICAL USER INTERFACE**

(71) Applicant: **Analytics For Life Inc.**, Toronto (CA)

(72) Inventors: **Ian Shadforth**, Morrisville, NC (US); **Meng Lei**, North York (CA); **Timothy Burton**, Ottawa (CA); **Don Crawford**, Fernandina Beach, FL (US); **Sunny Gupta**, East York (CA); **Paul Douglas Souza**, Novato, CA (US); **Cody James Wackerman**, Chico, CA (US); **Andrew Hugh Dubberly**, Palo Alto, CA (US)

(73) Assignee: **Analytics for Life Inc.**, Toronto (CA)

(**) Term: **15 Years**

(21) Appl. No.: **29/679,555**

(22) Filed: **Feb. 7, 2019**

Related U.S. Application Data

(63) Continuation of application No. 29/578,426, filed on Sep. 21, 2016, now Pat. No. Des. 843,382.

(57) **CLAIM**

The ornamental design for a display screen with graphical user interface, as shown and described.

DESCRIPTION

The FIGURE is a front view of a display screen with graphical user interface.

The broken lines showing the display screen and all numerals within graphical user interface illustrate the article of manufacture and portions of the graphical user interface, respectfully. None of the broken lines form part of the claimed design.
